US0D1061276S

(12) **United States Design Patent** (10) **Patent No.:** **US D1,061,276 S**
(45) **Date of Patent:** **** Feb. 11, 2025**

(54) **WRIST WATCH**

(71) Applicant: **Shenzhen Amazwear Technology CO., LTD.**, Shenzhen (CN)

(72) Inventor: **Xianghua Wu**, Wuhan (CN)

(73) Assignee: **Shenzhen Amazwear Technology CO., LTD.**, Shenzhen (CN)

(**) Term: **15 Years**

(21) Appl. No.: **29/967,443**

(22) Filed: **Oct. 10, 2024**

Related U.S. Application Data

(63) Continuation-in-part of application No. 29/902,988, filed on Sep. 19, 2023, now Pat. No. Des. 1,020,490, and a continuation-in-part of application No. 29/900,749, filed on Aug. 24, 2023, now Pat. No. Des. 1,020,489.

(57) **CLAIM**

The ornamental design for a wrist watch, as shown and described.

DESCRIPTION

FIG. 1 is a front, right and top perspective view of a wrist watch, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of portion 9 of FIG. 1 thereof; and,

FIG. 10 is an enlarged view of portion 10 of FIG. 2 thereof. The dot-dash broken lines depict the boundaries of the enlargements that form no part of the claimed design.

1 Claim, 10 Drawing Sheets
